United States Patent Office

Des. 226,718
Patented Apr. 17, 1973

226,718

TOY AIRPLANE

Jack G. McAllister, Minneapolis, Minn., assignor to
General Mills Fun Group, Inc.

Filed Sept. 8, 1971, Ser. No. 178,576

Term of patent 14 years

Int. Cl. D21—01

U.S. Cl. D34—15 HH

FIG. 1 is a perspective view of a toy airplane showing my new design;

FIG. 2 is a top plan view thereof;

FIG. 3 is a side elevational view thereof;

FIG. 4 is a rear elevational view thereof;

FIG. 5 is a front elevational view thereof; and

FIG. 6 is a bottom plan view.

I claim:

The ornamental design for a toy airplane, substantially as shown.
